HINGE STRUCTURE FOR TOILET SEATS AND COVERS

Francis J. Moore, Minneapolis, Minn.

Application July 17, 1940, Serial No. 346,017

8 Claims. (Cl. 4-236)

My present invention has for its object to provide an extremely simple, rugged and highly efficient hinge structure for attaching a seat and its cover to a closet bowl.

To the above end, the invention consists of the novel devices and combinations of devices hereinafter described and defined in the claims.

In the accompanying drawing, which illustrates the invention, like characters indicate like parts throughout the several views.

Referring to the drawing:

Fig. 1 is a plan view showing the improved hinge structure applied to a closet bowl, fragmentarily illustrated, and hingedly connecting a seat and its cover thereto;

Fig. 2 is a fragmentary view principally in rear elevation with some parts broken away and sectioned;

Fig. 3 is a fragmentary view partly in side elevation and partly in section taken on the line 20 3-3 of Fig. 2;

Fig. 4 is a view of the hinge structure partly in rear elevation and partly in section, on an enlarged scale;

Fig. 5 is a fragmentary detail view showing one of the abutments moved away from the tubing, on an enlarged scale;

Fig. 6 is a view partly in side elevation and partly in section taken on the line 6-6 of Fig. 4;

Fig. 7 is a plan view showing the two hinge members in blank form as they are stamped from a single rectilinear sheet of metal; and

Figs. 8 and 9 are views of the two hinge members in edge elevation.

The numeral 10 indicates, fragmentarily, a closet bowl having the customary pairs of transversely spaced holes 11 for hinge anchoring means. The seat for the bowl 10 and its cover are indicated by the numerals 12 and 13, respectively.

The improved hinge structure includes a fixed hinge member 14, a seat hinge member 16 and a cover hinge member 17. Said hinge member 14 is, as shown, a single round steel rod bent into the form of a yoke, the intermediate or transverse section of which is indicated by the numeral 15 and the legs thereof are indicated by the numeral 18. The lower or free end portions of the legs 18 are screw-threaded, as indicated at 19. Before the hinge member 14 is bent into the form of a yoke, a brass tubing 20 is telescoped onto the hinge member 14 and when said member is bent into its yoke-like form, said tubing covers the entire intermediate section 15 of said member and extends, at its end portions, part-

way downwardly on the legs 18. This tubing 20 not only strengthens the hinge member 14 but facilitates the finishing or plating thereof. The ends of the tubing 20 afford stops 21, as will presently appear.

A washer-like abutment 22 is telescoped onto each leg 18, at the screw-threaded end thereof, and has in its upper face an annular recess 23 adapted to receive the respective lower end portion of the tubing 20. The stops 21 limit the telescopic movement of the abutments 22 onto the legs 18 and the end portions of the tubing 20 have a tight fit with the abutments 22 in their recesses 23 and thereby frictionally hold said abutments against axial or turning movements on the legs 18. Said abutments 22 are also made of brass. The external contour of the abutments 22 are free from sharp edges or grooves so that they can be easily wiped and kept clean.

Recesses 24 in the under sides of the abutments 22 are provided to receive and cover rubber washers 25 that rest on the upper face of the bowl 10 and are of such thickness as to hold said abutments out of contact with the bowl 10. The legs 18 extend through the holes 11 in the bowl 10 and which holes are completely covered by the annular abutments 22 and sealed by the rubber washers 25. Said legs 18 are anchored to the bowl 10 by nuts 26 applied to the screw-threaded end portions of the legs 18 and draw the abutments 22 onto the bowl 10 and compress the rubber washers 25. These nuts 26 impinge against metal washers 27 on the legs 18 and rubber washers 28 are interposed between the under side of the bowl 10 and the washers 27. The legs 18, above the abutments 22 are curved upwardly and forwardly and correctly position the transverse section 15 of the fixed hinge member 14 relative to the seat 12 and its cover 13.

The seat hinge member 16 in plan is U-shaped and in edge elevation it is in the form of a right angle. The legs of the hinge member 16, at their outer end portions, are rolled to afford a pair of axially spaced hinge lugs 29 which are turnably mounted on the transverse section of the tubing 20. Stop pins 30 anchored in the hinge section 15 hold the hinge lugs 29 against axial shifting movement on the tubing 20. The rear end portion of the seat 12 extends into the angle formed by the hinge member 16 with the transverse portion of said member extending forwardly under said seat and secured thereto by screws 31.

The cover hinge member 17 in plan is in the form of the letter T and the outer end portion of the longitudinal section of said member is

rolled to afford a hinge lug 32 turnably mounted on the tubing 20 between the hinge lugs 29. Said hinge lugs 29 afford stops that hold the hinge lug 32 against axial movement on the tubing 20.

The transverse section of the hinge member 17 extends under the cover 13 and is secured thereto by screws 33.

Primarily the hinge lugs 27 and 32 are left open, as shown in Figs. 8 and 9, to permit their application around the tubing 20 by radial movement and thereafter said hinge lugs are further rolled around said tube to prevent the removal of the hinge members 16 and 17 therefrom.

By reference to Fig. 7 it will be noted that the two hinge members 16 and 17 are stamped from a single rectilinear sheet of metal without any waste whatsoever.

The drawing illustrates a commercial form of the invention, but it will be understood that the same is capable of certain modifications as to details of construction, arrangement and combination of parts within the scope of the invention herein disclosed.

What I claim is:

1. A hinge structure for attaching a seat to a closet bowl comprising a single hinge rod bent into the form of a yoke and having means for anchoring its legs to a closet bowl, and a seat hinge member pivoted to the transverse section of said rod.

2. A hinge structure for attaching a seat to a closet bowl comprising a single hinge rod bent into the form of a yoke and having means for anchoring its legs to a closet bowl, and a seat hinge member being applicable to the hinge rod between the legs thereof by movement transversely of the respective section of said rod.

3. A hinge structure for attaching a seat to a closet bowl comprising a single hinge rod in the form of a yoke and having means for anchoring its legs to a closet bowl, a tubular member surrounding the transverse section of the hinge rod and extending downwardly around the

legs thereof, and a seat hinge member pivoted to the transverse section of the tubular member.

4. A hinge structure for attaching a seat to a closet bowl comprising a single hinge rod in the form of a yoke, an abutment telescoped onto each leg of the hinge rod, a stop on each of said legs for the respective abutment thereon, a seat hinge member pivoted to the transverse section of said rod, and means on said legs co-operating with the abutments for anchoring the hinge rod to a closet bowl.

5. A hinge structure for attaching a seat to a closet bowl comprising a single hinge rod in the form of a yoke, a washer-like abutment telescoped onto each leg of the hinge rod, stops on the legs for the abutments thereon, the outer end portions of the legs being provided with screw-threads to receive nuts for co-operation with the abutments to anchor the hinge rod to a closet bowl, and a seat hinge member pivoted to the transverse section of the hinge rod.

6. A hinge structure for attaching a seat to a closet bowl comprising a single hinge rod in the form of a yoke, a tubular member surrounding the transverse section of the hinge rod and extending partway downwardly around the legs of the hinge rod, and washer-like abutments telescoped onto said legs and held by the ends of the tubular member as stops.

7. The structure defined in claim 6 in which the abutments at their upper faces are recessed to receive the end portions of the tubular member with a tight fit to frictionally hold the abutments relative to the hinge rod.

8. A hinge structure for attaching a seat and a cover therefor to a closet bowl comprising a single hinge rod bent into the form of a yoke and having means for anchoring its legs to a closet bowl, and a seat hinge member and a cover hinge member independently pivoted to the transverse section of the hinge rod.

FRANCIS J. MOORE.
